PORTABLE GRILL

Manley R. MaKenny, Beggs, and Billy Joe Duncan,
Tulsa, Okla., and Jay N. Smith, Wichita, Kans., as-
signors to Brunswick Corporation, Skokie, Ill.

Filed June 11, 1973, Ser. No. 368,599

Term of patent 14 years

Int. Cl. D7—02

U.S. Cl. D7—107

Fig. 1

Fig. 10

Fig. 11

Fig. 2

Fig. 3

Fig. 4

FIG. 1 is a perspective view of the portable grill while in the open position;

FIG. 2 is a perspective view thereof while in the closed position;

FIG. 3 is a front end elevation view thereof while in the open position;

FIG. 4 is a side elevation view thereof while in the open position;

FIG. 5 is a back elevation view thereof while in the open position;

FIG. 6 is a top plan view thereof while in the open position;

FIG. 7 is a bottom view thereof;

FIG. 8 is a top view thereof while in the closed position;

FIG. 9 is a back elevation view thereof while in the closed position;

FIG. 10 is a front elevation view thereof while in the closed position; and,

FIG. 11 is a side elevation view thereof while in the closed position.

FIGS. 1, 3, 4, 5 and 6 depict our new design for a portable grill while in the open position; FIGS. 2, 9, 10 and 11 depict the portable grill in the closed position; and, FIGS. 7 and 8 depict the top and bottom of the exterior surfaces of the grill whether opened or closed.

We claim:

The ornamental design for a portable grill, substantially as shown and described.
